UNITED STATES PATENT OFFICE.

GEORGE W. GRISWOLD, OF LOGANSPORT, INDIANA.

IMPROVED BRIDLE-HALTER.

Specification forming part of Letters Patent No. 35,932, dated July 22, 1862.

To all whom it may concern:

Be it known that I, GEORGE W. GRISWOLD, of Logansport, in the county of Cass and State of Indiana, have invented certain new and useful Improvements in Bridle-Halters; and I do hereby declare the following to be a full, clear, and exact description of the construction and operation of the same, reference being had to the accompanying drawings, making a part of this specification, in which—

Figure 1 represents a perspective view of the bridle and halter united; and Fig. 2 represents a perspective view of the halter, the bridle portion having been removed.

Similar letters of reference, where they occur in the separate figures, denote like parts of the bridle-halter in both of the drawings.

My invention consists in a "bridle-halter" so made as that the bit and its straps and reins may be readily attached to or detached from the other portions, leaving a halter upon the horse's head constantly, which need not be removed.

To enable others skilled in the art to make and use my invention, I will proceed to describe the same with reference to the drawings.

A A represent an ordinary halter, in which *a* are the side straps; *b*, the nose-strap; *c*, the ring-strap; *d*, the forehead-strap, and *e* the throat-latch strap. These straps are common on ordinary halters. To this halter I add a tablet, *f*, which may be connected to both the forehead-strap *d* and the side or head straps, *a a*, by means of a split strap, *g*, or in any other suitable manner; and to the tablet *f* is attached a ring, loop, or buckle, *h*, for sustaining and holding the bit, its straps, and reins when connected to the halter or headstall A.

The bridle portion B is composed of a bit or bits, *i*, the ordinary reins, *j*, a split strap, *k*, and a snap-hook, *m*, or some other device by which it may be attached to the ring, loop, or buckle *h* on the tablet *f*. It will be readily seen how quickly and easily this article is converted into a bridle and from a bridle into a halter. The halter or headstall A may remain on the horse's head constantly. To make it a bridle, the bit *i* is inserted into the mouth of the horse and the snap-hook *m* caught in the loop or ring *h*.

To remove the bridle, detach the snap-hook *m*, and the bit drops out of the horse's mouth, leaving the halter or headstall remaining. Thus the horse is always "haltered," and can the more conveniently be "bridled."

When the bit, reins, and bit-strap are detached, the snap-hook may be fastened to the ring *n*, and the horse hitched by it for a temporary fastening, or the snap-hook may be fastened to the hame-ring or terret of the harness without taking it entirely away, and where it is always convenient to be replaced, as occasion may require. For a more permanent fastening a strap or rope may be secured to the ring *n*.

This bridle-halter is much cheaper and less weighty than a bridle and halter in separate parts, as it dispenses with those parts of each that would be merely duplicates when separately made.

That the tablet *f* may not hurt the forehead of the horse it may be cushioned, and as a further security against any indentation by such snap-hook, buckle, or whatever other fastening may be used a metal plate may be interposed between the tablet and the pad or cushion under it. The strap *k*, instead of being fastened to the tablet or the forehead-strap *d*, may be fastened to the head-strap *a* by extending it that far, in which case the strap *g* might be dispensed with. By splitting the strap *k* both sides of the bit are held up by one fastening. The usual buckles and loops may be used for adjusting the several straps, or for uniting them into a whole.

Having thus fully described my invention, I would state that a bridle-halter has heretofore been made in which the bit was buttoned onto the nose-strap. This I do not claim; but

What I do claim in a bridle-halter is—

The straps *h k*, united to the bit and hooked or buckled to the head or forehead strap, the whole being constructed and operating substantially in the manner and for the purpose herein described.

GEO. W. GRISWOLD.
